UNITED STATES PATENT OFFICE.

HORATIO W. SOUTHWORTH, OF MITTINEAGUE, MASSACHUSETTS.

MOTOR-VEHICLE.

No. 820,444.

Specification of Letters Patent.

Patented May 15, 1906.

Application filed August 16, 1904. Serial No. 220,956.

To all whom it may concern:

Be it known that I, HORATIO W. SOUTHWORTH, residing at Mittineague, in the county of Hampden and State of Massachusetts, have invented certain new and useful Improvements in Motor-Vehicles, of which the following is a full, clear, and exact description, such as will enable others skilled in the art to which it appertains to make and use the same.

This invention relates to motor-vehicles and the means of propulsion thereof.

One of the objects is to provide in a motor-vehicle independent sources of power for use under varying conditions of running.

Another object is to provide a motor-vehicle in which a turbine may strongly and efficiently be mounted upon the axle thereof.

Another object is to provide a construction of the above nature in which the harmful effects of expansion of the several parts due to the heat of the turbine is neutralized.

Other objects will be in part obvious and in part pointed out hereinafter.

The invention accordingly consists in the features of construction, combinations of elements, and arrangement of parts which will be exemplified in the construction herein described and the scope of the application of which will be indicated in the following claims.

In the accompanying drawings, which illustrate two of various possible embodiments of my invention, Figure 1 is a front elevation of a motor-vehicle provided with a turbine mounted in accordance with my invention. Fig. 2 is a rear elevation of the same, showing a turbine mounted in a similar manner on the rear axle. Fig. 3 is a rear elevation of a motor-vehicle embodying my invention in a slightly-different manner. Fig. 4 is an enlarged section of a preferred type of turbine, showing stuffing-boxes and dust-protectors upon the same. Fig. 5 is a cross-section showing the same taken on the line $x-x$ of Fig. 4, part of the head thereof being broken away. Fig. 6 is an end view of a portion of a turbine, showing a slightly-different manner of connecting the same with the running-gear of a vehicle.

Similar reference characters refer to similar parts throughout the several views.

It may here be noted that among the most serious obstacles to the mounting of a turbine in a motor-vehicle are unequal ex-

pansion of the parts connecting the same to the running-gear and the harmful results from the drawing of dust and dirt into the stuffing-boxes upon the cooling of the same. This invention aims, broadly, to remedy these and other defects by equalizing the expansion of the several connecting parts and by the use of exterior dust-guards and the several other features hereinafter described. An example of constructions by which the above objects may be accomplished is shown in the accompanying drawings.

Referring now to Fig. 1, the wheels A are fixed at either end to the axle B, and extending over each wheel and resting upon the axle at either side thereof are arch-shaped supports 1. Detachably connecting the inner portions of these supports, as by flanges 2 and bolts 3, is a cross-bar 4, at the central portion of which is formed the lower member 5 of a fifth-wheel. Mounted above this cross-bar is what may be termed a "spring-bar" 6, having an upper fifth-wheel member 7 formed thereon or secured thereto at its central portion. Vehicle-body C is mounted upon spring-bar 6 by means of springs D, which are secured thereto by means of the nuts 8. The springs herein shown are of the longitudinal type, which has been found to be peculiarly adapted to this construction; but other forms of spring-gear may be used, if desired. It will thus be seen that the weight of the vehicle is transmitted to the axle at points closely adjacent the wheels and the bending or "springing" of the same reduced to a minimum.

Centrally positioned upon axle B is a turbine E, the construction of one form of which is shown in Fig. 4. The several cores 9, 10, and 11 are keyed to axle B and are proportioned in size substantially as shown. Surrounding these cores are cases 12, 13, and 14, which are rigidly secured one to another by means of bolts 15 passing through the projecting flanges thereof. These cases form the shell of the turbine. The end walls of the cases are journaled upon axle B by means of suitable bearings, and the customary blades or fans are formed upon the outer surfaces of the several cores and the inner surfaces of the corresponding cases in a well-known manner, as indicated at 16 and 17, respectively. Surrounding these shells is a casing or jacket 18, which has two heads 19 and 20. These heads are provided with

stuffing-boxes, of which, as they are identical, one only will be described. Upon the head 19 is formed an outwardly-projecting flanged collar 21, between which and the axle 5 B is inserted packing 22. A sleeve 23 fits the axle at a point immediately outside the packing 22 and is shaped so as to be adapted to be forced within the collar 21, as by means of bolts 24, between the outwardly-projecting flanges of these parts. The outer end of sleeve 23 is threaded, as shown, and upon the same is positioned a ring 25, having a depending flange 26, extending to a point nearly in contact with the axle B. Within this ring 15 and directly outside the outer end of sleeve 23 is a washer or gasket 27, preferably formed of felt or similar material and snugly fitted about the axle. This collar may be compressed to any desired extent by reason of the threaded connection between ring 25 and sleeve 23 and may readily be removed in an obvious manner.

Bolted to the heads of turbine E are braces 28, which are forked, so as to extend about 25 cross-bar 4, and the upper ends of which lie within sockets 28^a, secured to the inner sides of supports 1. A metallic spring or other elastic packing is preferably inserted in socket 28^a to take up lost motion and prevent rattling, and the braces are so proportioned in length that upon being heated by the turbine under normal running conditions they compress the spring or packing to its fullest extent.

30 Casing 18 is encircled at each end by straps 29, which are secured thereto and to radial braces 29^a by means of bolts or rivets 30. The inner ends of these braces are bent or flanged; as shown, and rigidly connected, 40 with the cases 12 and 14, thus preventing any relative movement between the shell and the casing or lagging surrounding the same. Straps 29 extend upwardly, as shown, and around the cross-bar 4, preventing any 45 relative lateral movement of the turbine with respect thereto.

The straps 29 are so formed and positioned with relation to the turbine that the expansion within the same between the axle B and 50 the cross-bar 4 is substantially equal one to the other and to that within arched supports 1 between the corresponding parts and due to the same effect. It will be noted that in this way the harmful effects of unequal expansion of the several connections between the axle and running-gear and consequent stress upon the parts and tendency to spring and cut the axle is neutralized.

55 Steam or other fluid under pressure is supplied to the turbine by means of a flexible connection 31, which may be of any desired form—as, for example, wire-wound hose. From the inlet 32 the steam is led through a valve 33 to the high-pressure steam-port 34

and thence in a direction indicated by the arrow in Fig. 4 to the exhaust-port 35 of the high-pressure chest. From this point the steam is led back through a passage (shown in dotted lines in Fig. 4) to the connection 36, which conducts the same to valve 37. The 65 steam or other fluid is led through the intermediate and low-pressure chest in a manner substantially identical with that described in relation to the high-pressure chest and is exhausted at 38, from which point it may be 70 conducted by a flexible connection 39 to a condenser or muffler, if desired. The precise construction of the valve mechanism above mentioned will not be shown or described, as it forms no part of the present invention, and any desired form of the same 75 may be used. The several connections and valves between the steam-pipe 31 and exhaust-pipe 39 are inclosed within the casing 18, as shown in Fig. 4, and the same is preferably provided with an extended or bulged portion, as shown in Fig. 5, so as to fit the several parts inclosed within the same more closely. In this way the air resistance of the casing is reduced and the wasteful radiation 80 of heat minimized.

At the lower side of the casing 17 is a boss 40, having a threaded projection or pin 41, projecting downwardly therefrom at a point directly under the center of the fifth-wheel. Secured to this pin by means of nut 42 is a 90 brace 43, which extends rearwardly and may be pivotally fastened to the vehicle-body in any desired manner.

In Fig. 2 is shown the rear-axle construction of the above vehicle, which differs from the above chiefly in the form of turbine used, and that the springs D, upon which the vehicle-body is supported, are mounted directly upon the cross-bar 4. This construction is allowable with reference to the rear axle, as no relative rotary movement between the same and the body is necessary. In this embodiment adjustable radius-rods 44 are pivotally secured to the body and to sleeves 45 upon the axle and perform the functions of brace 43 in the front-axle construction in maintaining the proper relative position of the axle and permitting free movement of the body with relation thereto. The construction and mounting of the rear-axle turbine is otherwise substantially the same as that described with reference to the front axle; but this turbine is preferably so constructed, as by a different angle of blades or in any other desired manner, as to run with a greater power and less speed than that upon the front axle. The advantage of this feature should be largely obvious, as it is well known that in order to obtain the maximum economy of running under some road conditions, as in hill-climbing, it is often necessary that the speed of the motive power

should be decreased and the force with which the parts thereof move correspondingly increased.

In Fig. 3 is shown a slightly-different embodiment of my invention, which is peculiarly adapted for use in connection with comparatively light vehicles, in which the supporting of the entire weight of the body with its associated parts upon the casing and shell of the turbine is permissible. In this construction the body F is mounted, by means of springs G, upon the outer ends of a cross-bar 46, which in turn is supported by means of straps 47 and 48. Adjustable radius-rods 15 are pivotally connected to the body and to sleeves upon the axle in this construction also. It will be understood in connection with this and the above-described embodiment that suitable reaches or other stiffening members may be used between the cross-bars, if desired. The turbine in this construction is substantially identical with that before described, and the straps 47 and 48 are so formed and positioned as to have equal expansion upon the heating thereof by means 25 of the turbine.

In Fig. 6 is shown a connection between a cross-bar 49 and a supporting-strap 50, whereby the former is engaged by a member 30 51, having a downwardly-extending socket 52. An upwardly-projecting lug 53 is formed on strap 50, positioned within this socket, and any slight movement between the cross-bar and the casing of the turbine will be permitted by reason of this connection. It will also be noted that in this manner the harmful effects of unequal expansion of the supporting-straps is avoided. It will be obvious that this construction is not adapted 40 for use in connection with the last-described embodiment.

The operation of my invention should be largely obvious and will be described with relation to the embodiment thereof shown in Figs. 1 and 2. Upon the steam entering 45 through flexible pipe 31 and valve 33 it passes through the first or high-pressure chest of the turbine and thence through the valve to the steam end of the intermediate 50 core of the turbine. Passing through this section in a manner substantially the same as that before described, the steam passes through the second valve and the low-pressure chest and is exhausted through pipes 38 and 39, as above described. Any desired 55 form of condenser or muffler may be used in connection with this invention, as the same forms no part thereof.

It will thus be seen that I have provided 60 apparatus whereby a turbine may be securely and efficiently mounted directly upon the front axle of a vehicle and yet none of the freedom of movement of the same sacrificed. It will also be noted that in this construction 65 the equalization of the expansion of the sev-

eral parts will prevent any undue stress tending to lift or depress the stuffing-box against the axle and result in the cutting or springing of the latter.

The value of the feature of having two turbines of different construction upon different axles of a vehicle, whereby the speed and power thereof may be varied without any adjustment of either source of power, should be largely obvious. It may here be noted that the additional turbine acts as a safeguard against the disabling of the vehicle by reason of the breaking down of the other.

The construction of the dust-protectors, whereby the dirt and dust, which is unavoidable in a construction of this type, is not only excluded from the interior parts of the mechanism, but is also prevented from entering the stuffing-boxes thereof, has marked advantages over structures now in use. It will also be noted that the shape of the lagging, whereby undue size and consequent air resistance is avoided and yet complete protection for the turbine and the connections between the several parts of the same is maintained, is highly advantageous and conduces to economy in steam consumption.

The several parts used are simple and easily assembled, and the entire mechanism is inexpensive and may be applied to vehicles now in use with few alterations.

By the word "turbine" as used throughout the following claims is meant any rotary non-reciprocating engine driven by an elastic fluid.

It is to be understood that the steering of the vehicle herein described may be accomplished in any desired manner—as, for example, by means of a chain attached to the axle at both sides of the pivotal connection and led about a sprocket-wheel mounted within the vehicle-body.

As many changes could be made in the above construction and many apparently widely different embodiments of my invention could be made without departing from the scope thereof, I intend that all matter contained in the above description and all shown in the accompanying drawings shall be interpreted as illustrative and not in a limiting sense. I desire it also to be understood that the language used in the following claims is intended to cover all of the generic and specific features of the invention herein described and all statements of the scope of the invention which as a matter of language might be said to fall therebetween.

Having described my invention, what I claim as new, and desire to secure by Letters Patent, is—

1. In combination, an axle, a non-reciprocating engine mounted thereon, a cross-bar above said axle, wheels on said axle, and means supporting said cross-bar on said axle at both sides of each of said wheels, said

- engine passing between said cross-bar and said axle.
2. In combination, an axle, a turbine mounted thereon, a cross-bar above said axle, 5 wheels on said axle, and means supporting said cross-bar on said axle at both sides of said wheels.
3. In combination, an axle, a turbine mounted upon said axle, a cross-bar above 10 said axle, wheels on said axle, and means supporting said cross-bar on said axle at points adjacent said wheels, said turbine passing between said axle and said cross-bar.
4. In combination, an axle, a turbine 15 mounted thereon, a cross-bar above said axle, wheels on said axle, and means supporting said cross-bar on said axle at both sides of each of said wheels, said turbine being connected to said cross-bar.
5. In combination, an axle, wheels mounted thereon, supporting members extending over said wheels and resting on said axle at either side thereof, a cross-bar detachably connecting said supporting members, and a 20 source of power adapted to drive said wheels.
6. In combination, an axle, wheels mounted thereon, supporting members extending over said wheels and resting on said axle at either side thereof, a cross-bar detachably 25 connecting said supporting members, and a source of power mounted on said axle.
7. In combination, an axle, a vehicle running-gear, a source of heat mounted adjacent said axle, and a plurality of connections between said axle and said running-gear, each connection being so proportioned and related to the associated parts and to said source of heat as to increase and diminish the distance between the parts of the axle and the running-gear with which they are connected under the varying influence of said source of heat in a substantially equal degree.
8. In combination, an axle, a cross-bar, a source of heat mounted adjacent said axle, 45 and a plurality of connections between said axle and said cross-bar and related to the associated parts and to said source of heat so as to increase and diminish the distance between the parts of the axle and of said cross-bar with which they are connected under the varying influence of said source of heat in a substantially equal degree.
9. In combination, an axle, vehicle running-gear, a source of heat mounted on said 55 axle, and a plurality of connections between said axle and running-gear, each connection being so proportioned and related to the associated parts and to said source of heat as to increase and diminish the distance between the parts of the axle and of said running-gear with which they are connected under the varying influence of said source of heat in a substantially equal degree.
10. In combination, an axle, a turbine 60 mounted thereon, and dust-protectors mounted on said axle at points outside said turbine.
11. In combination, an axle, a turbine mounted thereon, stuffing-boxes on said turbine, and dust-protectors mounted on said axle at points outside said stuffing-boxes.
12. In combination, an axle, a turbine mounted thereon, stuffing-boxes at each end of said turbine, sleeves adapted to vary the pressure upon the packing in said stuffing-boxes, and collars secured to said sleeves and adapted to retain dust-excluding means in operative position on said axle.
13. In a motor-vehicle, in combination, a plurality of axles, and a turbine mounted on each of said axles, each turbine being adapted 80 to run at a speed different from the others when all of said turbines are working at a maximum of efficiency.
14. In combination, an axle, a turbine mounted thereon having a plurality of chambers, connections between said chambers outside the shell of said turbine, and an outer casing adapted to cover said shell and said connections.
15. In combination, an axle, a turbine 85 mounted thereon having a plurality of chambers, connections between said chambers outside the shell of said turbine, and an outer casing fitting said shell and having an outward projection inclosing said connections.
16. In combination, an axle, a source of power connected therewith, a cross-bar mounted above said axle, wheels on said axle; means supporting said cross-bar on said axle at both sides of each of said wheels, a vehicle-body mounted on said cross-bar, and flexible connections between said body and said source of power.
17. In combination, an axle, a turbine mounted thereon, a cross-bar above said axle, 100 wheels on said axle, means supporting said cross-bar on said axle at both sides of each of said wheels, a vehicle-body mounted upon said cross-bar, and flexible connections between said body and said turbine.
18. In combination, an axle, wheels mounted thereon, supporting members extending over said wheels and resting on said axle at either side of each of the same, a cross-bar detachably connecting said supporting members, a turbine mounted on said axle, and an extensible connection between said turbine and said cross-bar.
19. In combination, an axle, wheels on 115 said axle, a cross-bar mounted adjacent said axle and supported thereon at each side of each of said wheels, a source of heat mounted adjacent said axle, and a plurality of connections between said axle and said cross-bar, each connection being so proportioned and related to the associated parts and to said source of heat as to increase and diminish the distance between the parts of the axle and of the cross-

bar with which it is connected under the varying influence of said source of heat in a substantially equal degree.

20. In combination, an axle, a turbine mounted thereon, dust-protectors mounted on said axle at points outside said turbine, wheels on said axle, a cross-bar above said axle, and means supporting said cross-bar on said axle at both sides of each of said wheels.

21. In a motor-vehicle, in combination, a plurality of axles, a turbine of different construction mounted upon each of said axles, a cross-bar mounted above one of said axles, wheels on said axle, and means supporting said cross-bar on said axle at both sides of each of said wheels.

22. In combination, an axle, a turbine mounted thereon having a plurality of chambers, connections between said chambers outside the shell of said turbine, an outer casing fitting said shell and having an outward projection extending over said connections, a cross-bar above said axle, wheels on said axle, and means supporting said cross-bar on said axle at both sides of each of said wheels.

23. In combination, an axle, a vehicle running-gear, a turbine mounted on said axle, dust-protectors on said axle at points outside of said turbine, and a plurality of connections between said axle and said running-gear, each connection being so proportioned and related to the associated parts and to said turbine as to increase and diminish the distance between the parts of the axle and of said running-gear with which they are connected under the varying influence of the heat of said turbine in a substantially equal degree.

24. In combination, an axle, a turbine mounted thereon, dust-protectors on said axle at points outside said turbine, wheels on said axle, a cross-bar adjacent said axle and supported thereon at both sides of each of said wheels, and a plurality of connections between said axle and said cross-bar, each connection being so proportioned and related to the associated parts and to said turbine as to increase and diminish the distance between the parts of the axle and of said cross-bar with which they are connected under the varying influence of the heat of said turbine in a substantially equal degree.

25. In a motor-vehicle, in combination, a plurality of axles, a turbine of different construction mounted upon each of said axles, wheels on said axles, a cross-bar mounted upon one of said axles at both sides of said wheels, and a plurality of connections between said axle and said cross-bar, each connection being so proportioned and related to the associated parts and to said turbine as to increase and diminish the distance between the parts of the axle and of said cross-bar with which they are connected under the varying influence of the heat of said turbine in a substantially equal degree.

ryng influence of the heat of said turbine in a substantially equal degree. 65

26. In a motor-vehicle, in combination, a plurality of axles, a turbine of different construction mounted upon each of said axles, each turbine having a plurality of chambers, connections between said chambers outside the shell of one turbine, an outer casing fitting said shell and having an outward projection extending over said connections, and a cross-bar mounted adjacent one of said axles and supported thereon at both sides of each of said wheels. 70

27. In combination, an axle, a turbine mounted thereon having a plurality of chambers, connections between said chambers outside the shell of said turbine, an outer casing fitting the shell of said turbine and having an outward projection extending over said connections, dust-protectors mounted on said axle at points outside of said turbine and adapted to coat therewith, a cross-bar mounted adjacent said axle, and a plurality of connections between said axle and said cross-bar, each connection being so proportioned and related to the associated parts and to said turbine as to increase and diminish the distance between the parts of the axle and of said cross-bar with which they are connected under the varying influence of the heat of said turbine in a substantially equal degree. 80 90

28. In a motor-vehicle, in combination, a plurality of axles, a turbine of different construction mounted upon each of said axles, dust-protectors on said axles outside of said turbines and adapted to coat therewith, wheels on said axles, a cross-bar adjacent one of said axles and supported thereon at both sides of said wheels, and a plurality of connections between said axle and said cross-bar, each connection being so proportioned and related to the associated parts and to said turbine as to increase and diminish the distance between the parts of the axle and of said cross-bar with which they are connected under the varying influence of the heat of said turbine in a substantially equal degree. 100 105

29. In combination, an axle, a turbine mounted thereon, dust-protectors on said axle outside of said turbine and adapted to coat therewith, said turbine being divided into a plurality of chambers, connections between said chambers outside the shell of said turbine, an outer casing fitting said turbine and having an outward projection extending over said connections, wheels on said axle, a cross-bar adjacent said axle and supported thereon at both sides of each of said wheels, and a plurality of connections between said axle and said cross-bar, each connection being so proportioned and related to the associated parts and to said turbine as to increase 115 120 125

and diminish the distance between the parts of said axle and of said cross-bar with which they are connected under the varying influence of the heat of said turbine in a substantially equal degree.

30. In a motor-vehicle, in combination, a plurality of axles, a turbine of different construction mounted upon each of said axles, dust-protectors on said axles at points outside of one turbine and adapted to coat therewith, said turbine comprising a plurality of chambers, connections between said chambers outside the shell of said turbine, an outer casing fitting the shell of said turbine and having an outward projection adapted to extend over said connections, wheels on said axles, a cross-bar mounted adjacent one of said axles and supported thereon at points adjacent each of said wheels, and a plurality of connections between said axle and said cross-bar, each connection being so proportioned and related to the associated parts and to said turbine as to increase and diminish the distance between the parts of the axle and of said cross-bar with which they are connected under the varying influence of the heat of said turbine in a substantially equal degree.

31. In a motor-vehicle, in combination, a vehicle-body, an axle, a turbine mounted on said axle, and vertically-alined pivotal connections between said axle and said vehicle-body.

32. In a motor-vehicle, in combination, a vehicle-body, an axle, a cross-bar mounted upon said axle, a pivotal connection between said vehicle-body and said cross-bar, a turbine mounted on said axle, and a pivotal connection between said turbine and said vehicle-body substantially vertically alined with said first-mentioned pivotal connection.

33. In a motor-vehicle, in combination, a vehicle-body, an axle, a turbine mounted on said axle and adapted to drive the same, a cross-bar mounted adjacent said axle and supported thereon at both sides of each of the wheels thereof, a pivotal connection between said cross-bar and said vehicle-body, and a second pivotal connection between said vehicle-body and the lower side of said turbine.

34. In combination, a vehicle-body, an axle, a cross-bar mounted adjacent said axle, a transverse spring-bar, springs adapted to support said vehicle-body upon said spring-bar, a pivotal connection between said spring-bar and said cross-bar, a source of power mounted on said axle, and a pivotal connection between a part of said source of power and said vehicle-body substantially vertically

aligned with said first-mentioned pivotal connection.

35. In a motor-vehicle, in combination, an axle, wheels upon said axle, supporting members resting upon said axle at points adjacent said wheels, a cross-bar mounted upon said supporting members and adapted to transmit thereto a portion of the weight of the vehicle-body, braces secured to the inner sides of said supports, and means upon said axle against which said braces are adapted to abut.

36. In a motor-vehicle, in combination, an axle, wheels upon said axle, supporting members engaging said axle at points adjacent said wheels, a cross-bar secured to said supporting members and adapted to transmit thereto a portion of the weight of the vehicle-body, sockets mounted upon said supports, braces resting in said sockets, and means upon said axle against which said braces are adapted to abut.

37. In a motor-vehicle, in combination, an axle, wheels mounted upon said axle, supporting members extending on either side of said wheels and resting upon said axle, a cross member mounted upon said supporting members and adapted to transmit a portion of the weight of the vehicle-body thereto, sockets upon the inner sides of said supporting members, elastic means inclosed in said sockets, braces adapted to rest in said sockets and engage said elastic means, and means upon said axle against which said braces are adapted to abut.

38. In a motor-vehicle, in combination, an axle, wheels mounted upon said axle, supporting members extending on either side of said wheels and resting upon said axle, a cross member mounted upon said supporting members and adapted to transmit a portion of the weight of the vehicle-body thereto, sockets upon the inner sides of said supporting members, elastic means inclosed in said sockets, braces adapted to rest in said sockets and engage said elastic means, and a turbine mounted upon said axle against the heads of which said braces are adapted to abut.

39. In combination, an axle, a non-reciprocating engine thereon, a vehicle-body, a cross-bar connected with said vehicle-body and supported upon said axle at each side of said engine, and means connecting said engine with said cross-bar.

In testimony whereof I affix my signature in the presence of two witnesses.

HORATIO W. SOUTHWORTH.
